UNITED STATES PATENT OFFICE.

JOSEPH C. FIELD, OF ORANGE, NEW JERSEY, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed November 14, 1921. Serial No. 514,954.

This invention relates to electromagnetic devices of the circuit controlling type.

It is an object of the invention to provide a new and improved relay which is adapted 5 to make and break a plurality of circuits simultaneously.

More specifically, the invention contemplates a relay which may be operated by currents of opposite polarity to perform a plurality of switching operations and to this end employs a bank of springs so disposed that alternate contacts are opened and closed, respectively, by an operation of the armature in each direction.

15 Another feature of the invention is a device which is quick and positive in action, and in which the contact springs may carry considerable current, necessitating sufficient pressure to insure proper conduction without 20 sparking and consequently employing relatively strong springs and electromagnetic devices having considerable power.

Other features of the invention relate to the details of construction and combination 25 of parts whereby a minimum number of parts are used, all of which may be easily formed and assembled.

Other objects and features of the invention will appear from a consideration of the following description taken in conjunction with the accompanying drawing and the appended claim.

In the drawing, Figs. 1 and 2 are top plan and side elevation views respectively of a device embodying the invention, the enclosing cover therefor being shown in section; and Fig. 3 is a detail perspective view of the armature employed in the device.

Referring to the drawing, 5 and 6 designate 40 the windings of an electromagnet controlling an armature 7 which is centrally pivoted in an inverted U-shaped member 8 mounted on the bracket 9. This armature is polarized by means of a permanent magnet 10.

Attached to the armature 7 is a bifurcated arm 11 carrying studs upon which are 45 mounted rollers 12 and 13 of insulating material which are each adapted to engage one contact spring of a spring pile-up 14. The coils 5 and 6 and the cores on which they are wound are supported in the bracket 9 which is mounted on a base 15. The spring pile-up 14 is mounted on a plate 16 fixed to the bracket 9 and comprises a plurality of spring 50 contact members suitably separated by means

of insulating strips 17 and held firmly in place by any suitable means, such as clamping screws 18. The pile-up comprises a pair of main springs 19 and 20 adapted to alternately engage contact springs 21 and 22 and 60 springs 23 and 24, respectively. The main springs 19 and 20 are at all times in engagement with the rollers 12 and 13 carried by the armature 7 and are flexed to normally engage the inner contact springs 22 and 23, 65 respectively, but are held out of engagement therewith and midway between their associated contact springs when the laterally moving armature 7 is in the neutral position shown in Fig. 1. Since the armature 7 is 70 normally biased, however, it will be evident that each main spring contact will always be in engagement with one or the other of its associated contact members. Thus when the armature is attracted by the energization of coil 6, main spring 19 will make with the associated contact spring 22, and main spring 20 will be moved into engagement with its associated contact spring 24. By this movement of the armature contact 21 75 will be opened and contact 22 closed, contact 23 opened and contact 24 closed. When armature 7 is moved by the energization of winding 5 the positions of the contact springs will be reversed, springs 21 and 23 being 80 closed and springs 22 and 24 being opened by main springs 19 and 20. Thus, although as previously noted, both main springs are so flexed as to normally engage their respective inner contact springs, still one main 85 spring will always be held in engagement with an outer contact against its normal tension even when the electromagnet is deenergized. This holding means is controlled by the magnetism in the permanent magnet 10 90 which polarizes the cores of the coils 5 and 6.

It is to be understood that the invention is not limited to two main springs and their associated contact springs, as banks of springs may be employed in any desired 100 number according to the number of circuits it is desired to control. By this arrangement of contact members adapted to be actuated by an armature, it will be seen that any number of electrical circuits may be 105 made and broken alternately and simultaneously.

The entire electromagnetic structure may be conveniently enclosed by a glass cover 25 which may rest upon a felt surface 26 110

carried by the base 15. This cover may be securely held in place by means of a rod 27 having a capped portion 28 resting on a felt washer 29, the rod passing between the 5 coils 5 and 6 and held by any suitable holding means, not shown in the drawing, beneath the base 15. The electrical connections with the coils and the spring pile-up may be made through a plurality of binding posts 30.

What is claimed is:

A relay comprising a pair of coils wound so that the cores have opposite polarity when energized, a movable armature, a permanent 15 magnet, one pole of which is adjacent said armature the other pole of which is connected to a fixed armature joining the cores of said coils, said armature when attracted making contact with a core and remaining

there upon the removal of the energizing current and a pair of sets of springs mounted on said device with the free ends in operative relation to said movable armature, each set comprising a middle spring and an inner and outer spring, the middle springs being tensioned to tend to engage the inner springs, the movable armature having a pair of insulating studs engaging said middle springs and when rocked forcing one middle spring out of contact with its inner spring and into contact with its outer spring and allowing the other middle spring to move away from its outer spring and engage its inner spring.

In witness whereof, I hereunto subscribe 35 my name this 10th day of November A. D., 1921.

JOSEPH C. FIELD.
